ATTORNEY

UNITED STATES PATENT OFFICE.

HERMAN L. HOHLFELD, OF PHILADELPHIA, PENNSYLVANIA.

DESIGN FOR A HAMMOCK.

40,797.

Specification for Design.

Patented July 26, 1910.

Application filed May 26, 1910. Serial No. 563,672. Term of patent 3½ years.

To all whom it may concern:

Be it known that I, HERMAN L. HOHLFELD, a citizen of the United States, a resident of the city of Philadelphia, in the county of Philadelphia and State of Pennsylvania, have invented a new, original, and ornamental Design for Hammocks, of which the following is a specification, reference being had to the accompanying drawing, forming part thereof.

The figure is a plan view of a hammock, showing my new design.

What I claim is:

The ornamental design for a hammock, substantially as shown.

HERMAN L. HOHLFELD.
